(57) **CLAIM**

The ornamental design for a vehicle wheel, as shown.

DESCRIPTION

FIG. 1 is a perspective view of a vehicle wheel according to an aspect of the disclosure; and,
FIG. 2 is a front view of a vehicle wheel according to an aspect of the disclosure.

The broken line showing of the bolt holes and the valve stem hole is included for the purpose of illustrating environment and forms no part of the claimed design.

1 Claim, 2 Drawing Sheets

FIG. 1

FIG. 2
